UNITED STATES PATENT OFFICE.

JULIUS JOHNSON, OF MESA, ARIZONA TERRITORY.

ORE-MILL.

No. 851,757.

Specification of Letters Patent.

Patented April 30, 1907.

Application filed March 12, 1906. Serial No. 305,540.

To all whom it may concern:

Be it known that I, JULIUS JOHNSON, a citizen of the United States, and a resident of Mesa, in the county of Maricopa and Territory of Arizona, have invented a new and Improved Ore-Mill, of which the following is a specification.

My invention relates to that class of mills which are intended and adapted for crushing, grinding, and thus pulverizing ore and other substances, the class being distinguished by a toothed, or armed, cylinder, or shaft, rotating in fixed bearings, and a greatly enlarged drum, or cylinder, inclosing such cylinder or shaft, and revolving around it by the impact or friction of the two.

The details of construction, arrangement, and operation are as hereinafter described, and illustrated in the accompanying drawings, in which

Figure 1 is a central longitudinal vertical section of my improved ore mill. Fig. 2 is an end view of the interior armed cylinder and the inclosing drum or cylinder supported and adapted to rotate thereon. Fig. 3 is a vertical transverse section on the line 3—3 of Fig. 1. Fig. 4 is a horizontal section of the mill. Figs. 5 and 6 are sectional views of portions of the peripheries of the outer and inner cylinders, respectively.

A horizontal shaft 1, see Figs. 1, 4, rotates in bearings supported upon pedestals 2 which may be constructed of any suitable material and which as indicated in Figs. 3 and 4 form part of a casing or inclosure 2^a for the mill. This shaft is provided with fast and idler pulleys as shown, but it is to be understood that in place of belt gearing for driving the shaft 1 may employ any other preferred mechanism. Upon the shaft is mounted a cylinder or drum A so as to revolve with it. The shell of this cylinder is preferably constructed of steel and its outer peripheral portion is formed of a series of parallel bars, Fig. 3, in the form of railroad rails, the same being arranged longitudinally of the cylinder as shown.

As indicated in several figures, see especially Fig. 6, the bases of the rails 3, which are flat are laid upon wooden blocks or strips 4, which are curved on their inner sides to conform to the periphery 5 of the cylinder A. The rails are secured by means of clamping pieces 6, which are laid between the rails and under-cut on opposite sides to receive the flanges of the latter, and screw-

bolts 7 which pass through the said pieces 6, between the wooden base pieces 4 and through the periphery 5 of the cylinder A. It will be seen that by this means the rails 3 are secured firmly in place while in use, but that they may be readily removed when worn, to provide for the substitution of others. The said bars or rails 3 constitute a working surface; in other words, they constitute so many dies or stamps which in the operation of the mill, act upon the ore or other material for reducing it. A drum B having more than twice the diameter of the before described cylinder A is mounted and chiefly supported upon the cylinder A. The periphery of this drum B is preferably formed of sheet steel and its inner working surface is formed of rails 8 similar in form to railroad rails, the same being laid parallel circumferentially and secured with their bases against the inner side of the drum. As shown in Fig. 5, the bases of the rails 8 are spaced apart and bolts 9 pass through the same for securing them detachably, so that they may be removed when required; as in the case of the rails 3 of the cylinder A, as described.

An annular screen 10—see Figs. 1, 2, 4—forms a portion of one end of the drum B, a large central opening being left as indicated. As further shown in Fig. 2, a portion of this screen 10 may be formed as a door 11, to facilitate admission to the drum when required. The other end of the drum is formed by an annular plate 10^a. The ore or other material to be reduced is fed into the drum B, through a spout 13 having a hopper 13^a, and projecting into the central opening, see Fig. 1. It will be seen that the weight of the large drum B is imposed upon the armed cylinder A, its rails 8 thus bearing directly upon the rails 3 of the cylinder A. The cylinder A being revolved with the shaft 1, it is obvious that a slower rotation will be imparted to the drum B, and thus the ore or other material contained in the latter will be carried up by centrifugal action and come between the meeting surfaces of the two parts A, B, and be subjected to a crushing, grinding or pulverizing action whereby the desired reduction is rapidly effected. In brief the drum B is driven by friction with the cylinder A and the speed of the latter may be very rapid, say 1000 revolutions a minute. Each of the rails 3 secured to the surface of the cylinder A constitutes what may

be termed an individual die or stamp which upon coming in contact with the large drum B, as they both revolve strikes with more or less force, thus increasing the crushing and 5 grinding effect desired. The ore is in any case exposed to the stamping, crushing and grinding action until it is reduced sufficiently to pass through the screen 10 and into an outside receptacle or it may be removed 10 through a door 11 provided in the screen as before described.

It is apparent that the operation of the mill is most effective without a great expenditure of power, since the weight of the 15 large drum with the contained ore is constantly imposed upon the cylinder A.

In order to prevent side sway or oscillation of the drum B, I provide flanged rollers 12—see Figs. 1, 3, 4^a the same being clamped upon 20 parallel shafts 12^a arranged horizontally in the outer casing 2. These shafts are preferably located a little below the plane of the axis of the drum.

In order to prevent too much ore or other 25 material accumulating in the drum B, I provide an automatic cut-off and improved lever or evener for the ore within the drum. For this purpose I employ a swinging bar 14, the central portion of the same being parallel to the periphery of the drum B, and the side arms being bent and extended laterally and upward to a pivotal point 15—see Figs. 1 and 3. Such points are located preferably at one side of the axis of the cylinder A and 35 slightly below the same. To the middle portion of one of the arms of the bar 14 is attached a plate 16, which when the free end of the bar raises to a sufficient height covers the mouth of the feed pipe 13 and thus arrests the flow of ore therefrom. In Figs. 1 and 3, the bar 14, as shown in full lines, is in such position that the mouth of the feed pipe 13 is uncovered; but when in the position shown by dotted lines, the mouth is covered 40 by the plate 16. By this means I provide an automatic-feed regulator which is simple, and equally effective in preventing the overloading of the mill. It will be seen that the central straight portion of the bar coming in contact with the ore which may be irregularly deposited and distributed on the bottom of the drum B, serves to level and spread the same, which operation facilitates the grinding and pulverizing action.

55 In practice the inner cylinder A may be filled with some material—say cement—for the purpose of increasing its solidity, and thus enabling it to resist more effectually the impacts or blows incident to rotation and 60 contact with the ore drum B resting and traveling thereon.

The mill may be operated with the expenditure of comparatively little power. It may be transported in a dismembered con-

dition, and thus set up in the mountains or 65 other place which would be inaccessible to large mills. It may also be constructed at comparatively small cost, and its grinding parts may be easily replaced when worn out. Further, such parts may be cheaply 70 constructed since they are individually an article of ordinary manufacture.

What I claim is—

1. The improved ore mill formed of a horizontal cylinder having its peripheral grinding portion formed of a series of bars extending transversely and parallel, and an inclosing drum resting, and its weight entirely supported upon, such cylinder, so that it constitutes the ore-crushing medium, said drum 80 having its grinding surface formed of a series of bars extending circumferentially parallel and thus in planes perpendicular to the bars of the cylinder, as described.

2. In a mill for the purpose specified, a rotatable cylinder, a series of rails similar to railroad rails and having flat bases and interposed blocks which are curved on the inner side and flat on the outer side to form a suitable bearing for the flat bases of the rails, and 85 bolts passing through said blocks and the periphery of the cylinder for securing the rails detachably to the periphery of the cylinder, substantially as described.

3. In a mill for the purpose specified, the combination with a horizontal rotatable cylinder, a drum inclosing the same and resting and traveling thereon, and a feed spout fixed to a suitable support and projecting through the open end of the drum below the cylinder, 90 of a feed regulator comprising a bar pivoted at its ends and having a middle portion which is out of alignment with said ends and adapted to come in contact with and sweep over the ore in the cylinder, and having a 95 plate secured to it and arranged in a vertical plane so that it is adapted, when the free end of the bar is raised, to cover the mouth of the feed spout and thus arrest the flow of material into the drum and lateral supports in 100 which said bar is journaled, substantially as set forth.

4. The combination, with the horizontal rotatable cylinder and a drum inclosing and resting upon the same and traveling therewith, of an ore leveler and distributor consisting of an angular bar whose ends are pivoted exterior to the drum, its side arms extended through the openings in the ends of the drum and its central portion being parallel to the periphery of the drum and so located that it may come in contact with accumulations of ore within the drum, substantially as described.

JULIUS JOHNSON.
